(57) **CLAIM**

The ornamental design for a wall mountable support, as shown and described.

DESCRIPTION

In a preferred embodiment, the nature of this product is a wall mountable support such as for a robe hook, a towel ring, a toilet paper holder, a single rung towel bar, a double rung towel bar, or the like.

FIG. 1 is a right, top, front perspective view of a wall mountable support according to my new design with hook environment shown in phantom;

FIG. 2 is a front elevational view thereof;

FIG. 3 is a right side elevational view thereof, the left side elevational view thereof being a mirror image of the right side shown;

FIG. 4 is a top plan view thereof, the bottom plan view thereof being a mirror image of the top view shown;

FIG. 5 is a rear elevational view thereof;

FIG. 6 is a right, top, front perspective view of the wall mountable support of FIG. 1 with paper holder environment shown in phantom;

FIG. 7 is a right, top, front perspective view of the wall mountable support of FIG. 1 with single bar environment shown in phantom;

FIG. 8 is a right, top, front perspective view of the wall mountable support of FIG. 1 with double bar environment shown in phantom; and,

FIG. 9 is a right, top, front perspective view of the wall mountable support of FIG. 1 with ring environment shown in phantom.

The broken line representations of rear mounting structure in FIG. 5, hook environment in FIGS. 1-5, paper holder environment in FIG. 6, single towel bar environment in FIG. 7, double towel bar environment in FIG. 8, and ring environment in FIG. 9 are for the purpose of illustration only, and form no part of the claimed design.
